INVENTOR
Frank C. Brennan
BY
Adam E. Fisher
ATTORNEY

UNITED STATES PATENT OFFICE.

FRANK C. BRENNAN, OF COHOES, NEW YORK.

COMBINATION STARTER AND IGNITION SWITCH.

Application filed May 21, 1921. Serial No. 471,398.

To all whom it may concern:

Be it known that I, FRANK C. BRENNAN, a citizen of the United States, residing in the city of Cohoes and State of New York, have invented new and useful Improvements in Combination Starters and Ignition Switches, of which the following is a specification, reference being had to the accompanying drawings.

10 This invention is a combination starter and ignition switch for automobiles, and the object is to provide a simple and efficient apparatus for these purposes which may be mounted on the dash of the automobile and 15 easily manipulated for either the purpose of operating the starting mechanism or for closing the electric current through the ignition system.

In the drawings:

20 Figure 1 is a front elevation, a section being broken away to show the arrangement of the interior.

Figure 2 is a rear elevation.

25 Figure 3 is a side elevation; a section being broken away to show the interior parts.

The invention consists of a suitable case 1, preferably constructed of wood or some other suitable material for the sides and back, and bakelite for the front. Shaft holes 30 2 and 3 are cut through the centers of the front and back plates 4 and 5, through which are journaled the reduced ends 6 and 7 of the rotor 8. This rotor is also made of wood and is sufficiently less in length than the distance between the front and back plates to 35 permit the rotor to be moved back and forth on the shaft ends 6 and 7 playing through the holes 2 and 3. Insulated starter contact springs 9 and 10 of brass are mounted interiorly on the back plate 5 on opposite sides of the hole 3, and one of these springs, as 9, is advanced beyond the spring 10 in order to normally hold the rotor 8 in its forward position toward the front plate 4 and thus 40 prevent accidental closing of the circuit. Electrical conductors 11 and 12 are extended from these springs, through the case and placed in circuit with the battery and starting motor. A brass contact disk 13 is mounted over the shaft end 7 and is adapted to 45 close the starter circuit when the rotor 8 is pushed back in the case 1, thus connecting the springs 9 and 10. Interiorly, on one side

of the case are mounted two insulated ignition contact springs 14 and 15, and upon 55 two opposite sides of the rotor 8 are mounted contact strips 16 and 17. Conductors 18 and 19 lead from the springs 14 and 15 through the case and are placed in circuit with the ignition system. A push button 60 20 is mounted at the outer extremity of the reduced end 6. The device is to be mounted on the dash of the automobile.

In operation, the starting motor is set in motion by pushing inward on the button 65 20, after which the engine is started by rotating the rotor 8 until one of the strips 16 or 17 comes into contact with and connects the springs 14 and 15. The advanced spring 9 serves to hold the rotor 8 in its forward 70 position and prevents accidental closing of the starting circuit.

While I have herein described a certain specific method of constructing and assembling the elements of my invention, it is understood same may be varied in minor details, not departing from the spirit of my invention as defined in the appended claim.

I claim:

A combination starter and ignition switch 80 for automobiles, comprising a casing adapted for mounting on the automobile; shaft holes in the front and back thereof; a rotor with reduced shaft ends journaled in the casing by extending the said reduced ends 85 through the said shaft holes, the said rotor being shorter than the distance between the front and back of the casing so as to permit the rotor to be moved back and forth within the casing; insulated starter contact springs 90 mounted interiorly at the back of the casing, one of said springs being advanced beyond the other; a contact disk mounted on the back of the rotor and adapted to connect the starter contact springs when the rotor is 95 pushed back; two insulated ignition contact springs mounted interiorly on one side of the casing; two contact strips mounted oppositely on the rotor and adapted to connect the ignition contact springs when the rotor 100 is rotated.

FRANK C. BRENNAN.
